DRAFTING MACHINE

Charles H. Little, Cleveland Heights, Ohio, assignor of one-tenth to Charles Hubbard Little, Cleveland Heights, Ohio

Application February 15, 1936, Serial No. 64,141

7 Claims. (Cl. 33—79)

The present invention relates to drafting machines, and more particularly to drafting machines having a parallel motion arm or mechanism of the wheel and band type, wherein the parallel motion mechanism consists of a plurality of parallelograms comprising wheels operatively connected by flexible bands.

An object of the present invention is the provision of a drafting machine of the wheel and band type having struts of novel construction which will not bend sidewise under the stresses to which they are subject in operation, and form covers for the top and outside of the bands but are open at the bottom thereby being free of any tendency to collect and retain dirt, and facilitating assembly and adjustment of the band, etc.

Another object of the invention is the provision of a novel drafting machine of the wheel and band type wherein the struts are so constructed that they will not bend sidewise under the stresses to which they are subject in operation, and are initially stressed by the bands, especially the strut of the anchor parallelogram, in such a manner as to reduce the sag of the arm, particularly at the elbow.

Another object of the invention is the provision of a novel drafting machine of the wheel and band type having a strut comprising end sections to which the wheels are operatively connected and side rods covering the bands, in combination with a band including a turnbuckle link for adjusting the length thereof, and an operative connection between the bands and the side rods for preventing rotation of the band when the turnbuckle link is turned.

Another object of the invention is the provision of a novel band for a drafting machine of the wheel and band type comprising a plurality of members encircling the wheels provided with means for adjusting the length of the band and equalizing the tension between the members.

Another object of the invention is the provision of a novel anchor for attaching a drafting machine to a drawing board or table, which can be applied to boards of different thickness, and can be readily adjusted along the upper edge of the board from the draftsman's position at the front thereof.

Another object of the invention is the provision of a novel protractor assembly comprising a holding plate, a ruler assembly rotatably supported by said holding plate, and a protractor ring carried by said holding plate and adapted to be rotatably adjusted relative thereto, where-

by the zero mark on the protractor may be set at any desired angle and the subsequent readings determined therefrom.

The present invention resides in certain novel details of construction, and combinations and arrangements of parts, and further objects and advantages thereof will be apparent from the following description of the preferred embodiment thereof described with reference to the accompanying drawings forming a part of this specification, in which similar reference characters designate corresponding parts throughout the several views and in which:

Fig. 1 is a plan of a drafting machine embodying the present invention;

Fig. 14 is a section on the line 14—14 of Fig. 12, and

Fig. 15 is a view similar to Fig. 11 showing a strut of modified construction.

While the drafting machine herein illustrated and described is the preferred embodiment of the present invention, it is only illustrative of the invention which, it is to be understood, can be otherwise embodied, and I do not wish to be limited to the particular construction shown.

Briefly stated, the drafting machine shown comprises a parallel motion mechanism or arm provided at one end with an anchor for attachment to a drawing board or the like, and at the other end with a protractor assembly including rulers, etc. The parallel motion mechanism or arm consists of two parallelograms comprising

- flexible bands, designated generally by the reference characters A and B, encircling grooved wheels 10 and 11, and 12 and 13, respectively, of equal diameter and held apart or in spaced relation by frame members or struts C and D. The flexible bands A and B are alike in construction and, as shown, each comprises a flat flexible steel band 16 encircled by a flexible cable band 17 which makes two loops about the wheels.
- 10 The respective ends of the flat steel band 16 and the cable band 17 are connected together through the medium of a single take-up or turnbuckle link for adjusting the length of the band, and equalizers for distributing the tension equally therebetween.
- 15 The construction of the take-ups and equalizers is clearly shown in Figs. 6 and 7. Both ends of the flat steel band are reenforced by members 18 secured thereto in any suitable manner, and the ends of the cable band 17 are provided with terminal members 20. The ends of the flat steel band 16 and the cable band 17 adjacent each other are connected to opposite ends of equalizer cables 21 and 22 through the medium of members 23 and 24 detachably connected to provide for replacement, etc., to the members 18 and 20, respectively, as by screws 25. The equalizer cables 21 and 22 pass over small sheaves 26 rotatably supported on pins 28 secured in the forked ends of members 29 provided with tapped apertures into which opposite ends of the turnbuckle link 30 provided with right and left hand threads are threaded. A hexagonal portion intermediate the threaded ends of the turnbuckle link 30 provides means for rotating the same, and rectangular members 31 fixed to the members 29 and engaging within the channel of the side members or rods of the struts prevent rotation of the cable when the turnbuckle link 30 is rotated.
- 35 40 The members 31 are cut out at 32 as clearly shown in Fig. 9 in such a manner that they will not interfere with the free movement of the upper loop of the cable 17. While in the preferred embodiment illustrated two equalizers are employed in each band, one at either end of the take-up, it will be understood that in some instances one equalizer in each cable will be sufficient. This is especially true when a cable making only one loop about the wheels is employed
- 45 50 rather than two loops, as illustrated. From the foregoing, it will be apparent that the length of the bands A and B can be adjusted by rotating the turnbuckle link 30 therein and that the tension in the various parts of each band is at all times equalized.
- 55 The upper wheel 10 of the anchor parallelogram, which in some respect forms a part of the anchor mechanism, may be formed either integral with the anchor proper, as illustrated, or separate and secured thereto, as desired. The wheel 11 at the elbow of the arm is held in spaced relation to the wheel 10 by the one-piece strut C preferably stamped from a single piece of sheet metal. The strut preferably has the center thereof cut away to reduce the weight of the same but may be continuous, as shown in Fig. 15. The preferred construction of strut is clearly shown in Fig. 11 and consists of two disk-like end sections 35 and 36 provided with central apertures defined by cylindrical flanges 37 and 38, respectively, the former of which has an inturned flange 34 formed thereabout. The disk-like end sections 35 and 36 are connected by channel side rods or members 39 and 40 of inverted U-shaped cross section formed integral therewith. The in-

side flanges 41 and 42 of the side rods 39 and 40 continue around the inside of the disk-like end sections 35 and 36, forming thereon flanges 43 and 44, respectively, and the outside flanges 45 and 46 of the side rods continue around the ends of the strut forming outside flanges 47 and 48 on the end sections 35 and 36, respectively. As shown the outside flanges 45 and 46 have a plurality of lugs 49 formed integral therewith which help to retain the band within the channel of the side rods and prevents it from flying about and possibly injuring the draftsman in the event it should break. The strut may be varied in construction from that shown, as will be apparent to those skilled in the art, and the side rods 39 and 40 where employed may be of any desired shape.

The upper end of the strut C is pivotally connected concentric with the wheel 10 to a cylindrical projection or member 52 formed integral with the wheel, through the medium of an anti-friction bearing comprising balls 53 retained between inside and outside races 54 and 55. The inside race is secured on the member 52 in any suitable manner, as by a plate 56 secured to the member 52 by a screw, and the outside race is fixed within the flange 37 in a similar manner by a disk-like member 57, secured to the end section 35 by screws 58 threaded into a ring member 59 located underneath the strut. The member 57 covers the bearing and in addition to excluding dirt, presents a finished appearance. The wheel 11 is rotatably supported in the lower disk-like end section 36 of the strut C through the medium of an anti-friction bearing comprising balls 60 retained between inside and outside races 61 and 62. The inside race 61 is fixed, as by a forced fit, on a cylindrical hub or projection 63 formed integral with the wheel 11, and the outside race 62 is secured in a like manner within the flange 38. The bearing is provided with a cover plate 64 secured to the upper end of the hub 63 by a screw 65.

The strut C of the anchor parallelogram may be strengthened as desired. In the event that the entire weight of the arm and protractor assembly is carried from the anchor, as is often the case since this facilitates movement of the protractor assembly about the drawings, it is especially desirable to strengthen the anchor strut. In the embodiment illustrated, the upper ends of the side rods 39 and 40 are provided with short outwardly extending flanges 68 and 69 formed integral with the lower edge of the outside flanges 45 and 46 thereof, and with short inwardly extending flanges 70 and 71 formed integral with the lower edge of the inside flanges 41 and 42. The flanges 70 and 71 continue around the flange 43 forming thereon a flange 72.

The present invention also contemplates the elimination of the sag at the elbow of the arm, or at least a reduction thereof, by placing the anchor strut under stress in the reverse direction by raising one or both of the bearings above the centerline of the band. As illustrated only the bearing at the anchor is raised, and the upper side of the strut is placed under compression and the lower side thereof under tension. The amount of stress imparted thereto can be varied either by increasing the tension on the band or by increasing the height of the bearing above the centerline of the band. The proper height of the bearing above the band can be readily determined in each instance. In the drawings the bearing is raised an amount designated as X.

The one-piece protractor strut D is similar in construction to the anchor strut C and comprises two disk-like end sections 80 and 81 provided with central apertures defined by cylindrical flanges 82 and 83, respectively. The disk-like end sections are connected by channel side rods 84 and 85 of inverted U-shaped cross-section formed integral therewith. The inside flanges of the channel-shaped side rods 84 and 85 continue around the inside of the disk-like end sections 80 and 81, forming thereon flanges 88 and 89, respectively, and the outside flanges of the side rods continue around the ends of the strut forming outside flanges 92 and 93 on the end sections thereof, 80 and 81, respectively. Like the strut C, the strut D may be varied in construction from that shown, as will be apparent to those skilled in the art, and the rods 84 and 85 may be of any desired shape.

The wheel 12 of the protractor parallelogram has a cylindrical hub 94 formed integral therewith secured, as by a forced fit in a cylindrical aperture formed in the underside of the wheel 11. The left-hand end of the strut D is pivotally connected concentric with the wheel 12 to the cylindrical hub 94 thereof through the medium of an anti-friction bearing comprising balls 96 retained between inside and outside races 96 and 97. The inside race 96 is secured on the hub 94 as by a force fit, and the outside race is retained within the flange 82 in a similar manner. The wheel 13 is provided with a tubular hub 99 formed integral therewith and through the medium of which it is rotatably supported in the right-hand disk-like end section 81 of the strut D by an anti-friction bearing comprising balls 100 retained between inside and outside races 101 and 102. The inside race 101 is secured on the tubular hub 99 as by a force fit, and the outside race 102 is secured within the flange 83 in a like manner.

The protractor assembly comprises a disk-like holding plate 109 provided with a hub 110 fixed to the hub 99 of the wheel 13 above the end section 81 of the strut in any convenient manner, as by being forced thereon. A protractor ring 111 provided with the usual graduations is rotatably supported on the upper face of the disk-like holding plate 109 and is adapted to be clamped in any adjusted position thereon by a pair of clamps comprising members 112 positioned underneath thumb screws 113 threaded into tapped apertures in projections 114 on the sides of the holding plate 109. The members 112 project slightly over the upper surface of the protractor ring 111 and clamp the same therebetween and the holding plate 109 when the thumb screws 113 are tightened.

The ruler arms 115 and 116 carry rulers 117 and 118, respectively, of conventional construction detachably secured thereto in any well known manner. They are formed in one piece and are fixed to the lower end of a stub shaft 120 projecting upwardly through a cylindrical opening in the hub 99 of the wheel 13. A second disk-like member 121, formed in two pieces, as shown, or in a single piece, as desired, is fixed to the shaft 120 above the disk-like holding plate 109. The periphery of the member 121 engages in a groove formed in the protractor ring 111, and is provided with a dead line mark 122 for setting the rulers. A hand grasp 123 secured to the disk-like member 121 facilitates manipulation of the instrument. A dead line mark 124 formed on a member 125 fixed to the periphery of the holding

plate 109 and projecting over the protractor ring 111 facilitates the setting of the protractor ring at any desired angle. The rulers may be clamped in any angular position by a clamp comprising a winged nut 128 threaded onto a headed screw 129 provided with two washer-like members 130 and 131, adapted to clamp the protractor ring 111 and the periphery of the disk-like member 121 therebetween.

The present invention also contemplates an anchor that can be adjusted along the upper edge of the board from the draftsman's position at the front thereof. The advantages of this construction will be apparent to those familiar with the art to which the invention relates. Referring to Figs. 2 and 3, particularly, the anchor proper, consists of a channel-shaped bracket 135 adapted to receive the upper edge of the drawing board 136 between the upper and lower flange thereof. The bracket 135 is clamped to the board 136 by two wedge-shaped clamps 137 and 138, the upper flat faces of which are adapted to engage the underside of the board. The lower inclined surfaces or faces of the wedges engage an inclined surface on the upper side of a member 140, supported on two screws 144 and 145 threaded into the lower flange of the bracket 135 and rotatably secured to the under surface of the member 140. The screws 144 and 145 provide vertical adjustment of the member 140, thereby readily adapting the anchor for use with boards of various thickness. The wedges 137 and 138 are reciprocated to clamp and unclamp the board by screws 141 and 142 respectively, threaded therein and rotatably and slidably supported, but fixed against longitudinal movement in the bracket 135.

When it is desired to shift the anchor along the upper edge of the board, the draftsman grasps the screws 141 and 142, one of which is preferably provided with left hand threads, without changing his position at the front of the board. After the screws have been loosened they can be used as handles for shifting the anchor to the desired position. In shifting the anchor along the upper edge of the board the draftsman naturally pulls the screws towards the front of the board and in so doing keeps the anchor in close contact with the upper edge of the board, at all times. When the member 140 has been adjusted, by the screws 144 and 145, for any given board it will usually be unnecessary to touch the same again until the drafting machine is moved to a board of different thickness.

The modified form of strut previously referred to, having a continuous upper surface except for the apertures within which the bearing races are secured, is shown in Fig. 15. This strut consists of a metal stamping 150 having a continuous upper surface except for the apertures defined by the downwardly projecting flanges 151 and 152 adapted to receive the bearing races, and a flange 153 extending entirely around the periphery of the strut.

From the foregoing description of the preferred embodiment of the invention, it will be apparent that the objects of the invention have been accomplished and that a novel drafting machine which can be readily adjusted along the upper edge of the board has been provided, in which the parallel motion mechanism or arm is light, strong, capable of being readily assembled and disassembled, and which gives a high degree of stability to the rulers. The bands are covered, which, in addition to presenting a finished appearance, protects the operator in the event they should break.

in operation. Since the struts open downwardly, there is no tendency for dirt to collect therein.

While the preferred embodiment of the invention has been illustrated and described in some detail, I do not wish to be limited to the particular construction shown which may be varied within the scope of this invention. Numerous changes in the construction shown will readily suggest themselves to those skilled in the art to which the invention relates, and it is my intention to cover all variations, adaptations, and uses thereof that come within the practice of those familiar with this art.

I particularly point out and claim as my invention the following:

- 15 1. A drafting machine comprising a parallel motion arm, said parallel motion arm comprising a pair of wheels, a band comprising a flat metal band encircled by a flexible cable band encircling said wheels, a strut consisting of a one-piece member operatively connected to said wheels for maintaining the same in spaced relation, and anti-friction bearings interposed between said wheels and said strut.
- 20 2. A drafting machine comprising a pair of wheels, a flexible band encircling said wheels, and a strut operatively connected to said wheels for maintaining the same in spaced relation, said strut comprising a one-piece member including disk-like end sections overlying said wheels and connected by side members of inverted U-shape enclosing said band.
- 25 3. A drafting machine comprising a parallel motion arm, said parallel motion arm comprising a pair of wheels, a strut operatively connected to said wheels, a compound flexible band operatively connected to said wheels, said band comprising two separate members encircling said wheels and means for automatically equalizing the tension therebetween.
- 30 4. A drafting machine comprising a parallel motion arm, said parallel motion arm comprising a pair of wheels, a strut operatively connected to

said wheels for maintaining the same in spaced relation, a flexible band operatively connected to said wheels, said flexible band comprising a flat metal band and a cable band encircling said flat band, and means for automatically equalizing the tension between said flat band and said cable band.

5 5. A drafting machine comprising a pair of wheels, a flexible band encircling said wheels, and a strut operatively connected to said wheels by bearings adjacent the opposite ends of the strut for maintaining the wheels in spaced relation, the mid-plane of one of said bearings being above the mid-plane of the band.

10 6. A drafting machine comprising a jointed arm, a protractor assembly connected to one end of said arm, an anchor for connecting the other end of said arm to a drafting table, said anchor comprising a bracket, means for detachably clamping said bracket to the upper or rear edge of a drafting board, said means comprising a screw rotatably supported against longitudinal movement in said bracket with the head thereof projecting to the rear and the shank adapted to project underneath the board, and a wedge-like member having threaded engagement with the shank of said screw.

15 7. An anchor for a drafting machine comprising a bracket, means for detachably clamping said bracket to the upper or rear edge of a drafting board, said means comprising a screw rotatably supported against longitudinal movement in said bracket but movable vertically in said bracket with the head thereof projecting to the rear and the shank adapted to project underneath the board, means for preventing longitudinal movement of said screw, a tapered gib having threaded engagement with the shank of said screw, a backing member for said gib, and means for adjusting said backing member to raise or lower said gib.

30 35 40 CHARLES H. LITTLE.
